UNITED STATES PATENT OFFICE.

JOHN KRANS, OF CONNEAUT, OHIO.

STEEL-WORKER'S SAFETY DEVICE AND GLASSES.

Application filed December 15, 1928. Serial No. 326,379.

My present invention has reference to a protector device designed especially for use by men working in steel mills and particularly to riveters in such mills, and is designed 5 to prevent sparks from burning the workman's face or forehead.

A further and important object is the provision of a device for this purpose in which a forehead piece has hinged to the lower 10 corners thereof, in a novel manner, a shade which carries goggles so that the shade may be lifted, should occasion require without necessitating the removal of the device from the head of the user, and further wherein 15 the headpiece is lined to prevent excessive heat and the shade is so constructed that perspiration or sweat from the user will be directed away from his eyes and from the goggles carried by the shade and thereby 20 prevent the user from becoming blinded by perspiration.

A still further and important object is the manner in which the brim of the shade is hingedly secured to the forehead piece so 25 that the shade may be raised and sustained at desired inclinations on the forehead piece, and further wherein the limit of the downward movement of the shield, that is, to operative position, is limited by the contact with 30 a rim or roll on the lower edge of the forehead piece.

A still further object is the provision of a device for this purpose which may be easily and quickly arranged upon the forehead of 35 the user, adjusted to compensate for different sizes of users and firmly held positioned.

To the attainment of the foregoing and other objects which will present themselves 40 as the improvement is better understood, the invention consists in the improvement hereinafter described and definitely claimed.

In the drawings:

Figure 1 is a side elevation illustrating 45 the application of the improvement.

Figure 2 is a top plan view of the improvement.

Figure 3 is a sectional view approximately on the line 3—3 of Figure 1, the goggle 50 carrying shield being raised with the supporting brim therefor.

Figure 4 is a somewhat enlarged sectional view approximately on the line 4—4 of Figure 1.

55 The forehead piece of the improvement, indicated by the numeral 1, is arched both

transversely and longitudinally and is otherwise shaped so that the same will snugly be received on the forehead of the user. The forehead piece 1 has its edges rolled, as at 2, 60 the said roll providing what may be termed a rim and this rim engages and holds on the inner face of the forehead piece a lining 3 of velvet or the like. At its corners the forehead piece is provided with openings for the 65 reception of the ends of straps 4 which are preferably of elastic material and the ends of these straps are engaged by a buckle 5 whereby the forehead piece may be held adjusted on the forehead of the user. The 70 lower edge of the forehead piece is disposed directly above the eyebrows of the user and the rear edge of the forehead piece covers approximately one-third of the length of the head of the user. The head of the user is 75 covered by the usual leather head piece commonly worn by riveters in mills and elsewhere. The corners of the forehead piece, above the lower rim therefor, are each provided with spaced slots and are slightly 80 rounded inwardly, as at 6, between these slots. The slots have passed therethrough the offset ends 7 of metal plates 8. These metal plates have screwed, riveted or otherwise secured on their inner face dished metal 85 springs 9. The spring is pivoted, as at 10, to the plate 8. Overlying the plate 8 and engaged by inwardly directed ears 11 on the ends of the said plate (which is, of course, passed through suitable openings) there are 90 the inner and widened ends 12 of the metal brim 13 of the improvement.

As disclosed by Figure 2 of the drawings the brim is wider than the head piece and extends a suitable distance therebeyond. The 95 flange 14, which carries the enlargements 12, is concaved to correspond with the shape of the head piece. A brim hinged as above described may be sustained at any desired angle on the headpiece but the downward movement of the brim, that is, when the brim is brought to operative position, is designed to be brought into contact by the lower roll or rim 2 on the head piece 1 which not only limits the swinging of the brim in such direction 105 but prevents the shield, now to be described, from contacting with the upper portion of the face of the user with unnecessary friction.

The shield, indicated by the numeral 15, 110 is shaped to correspond to the upper contour of the face of the user and to overlie the nose
